UNITED STATES PATENT OFFICE.

LE ROY BROWN, OF LANSING, MICHIGAN.

EXPLOSIVE-ENGINE.

1,213,736.

Specification of Letters Patent. Patented Jan. 23, 1917.

Application filed April 3, 1916. Serial No. 88,692.

To all whom it may concern:

Be it known that I, LE ROY BROWN, a citizen of the United States, residing at Lansing, in the county of Ingham and State of Michigan, have invented a new and useful Explosive-Engine, of which the following is a specification.

This invention relates to explosive engines and more especially to the construction of the jacket surrounding the cylinders, one object being to provide a novel arrangement of passages whereby the exhaust gases can be directed through the jacket and will serve to maintain the gaseous fuel at a high temperature.

15 A further object is to provide means whereby the water used as a cooling medium will not extend between said passages and the outer wall of the jacket, but overheating and warping of said wall will be prevented by steam generated in the jacket, so that it becomes possible to maintain the gaseous fuel at a higher temperature than could be attained should water only be used as a cooling medium.

20 With the foregoing and other objects in view which will appear as the description proceeds, the invention resides in the combination and arrangement of parts and in the 30 details of construction hereinafter described and claimed, it being understood that changes in the precise embodiment of the invention herein disclosed, can be made within the scope of what is claimed, without departing from the spirit of the invention.

25 In the accompanying drawings the preferred form of the invention has been shown.

In said drawings:—Figure 1 is a view 40 partly in plan and partly in section of the cylinder casting of an engine. Fig. 2 is a view partly in elevation and partly in section of said cylinder casting. Fig. 3 is a view partly in end elevation and partly in 45 section of the casting, the section being taken on the line A—B Fig. 1.

Referring to the figures by characters of reference 1 designates a cylinder casting of the usual construction having spaced exhaust passages 2 between which is provided a fuel intake port 3 opening into a chamber 4. Valves 5 are provided for closing the exhaust passages and additional valves 6 are utilized for controlling the flow of fuel from 50 the chamber 4 to the respective cylinders.

55 The usual water jacket is employed but

the water contained within the jacket is not designed to flow between the chamber 4 and the passages 2. Instead a partition 7 extends within the casting so as to divide the 60 water jacket into a water containing chamber 8 and a steam chamber 9, this steam chamber being arranged between the partition 7 and the adjacent side wall of the cylinder casting. A desired number of ports 10 65 are provided within the partition 7 and each of these ports is designed to be partly or entirely closed by a valve 11 the stem 12 of which extends through the wall of the casting and may be rotated in any suitable 70 manner, as by means of a wheel 13.

While the engine is in use the valves 11 are moved so as to permit the leakage of a small amount of water from the chamber 8 into the chamber 9 and as the walls of the 75 casting are heated to a high temperature by the hot gases exhausted therefrom, it will be apparent that as the water is admitted in small quantities to the chamber 9 it will be immediately converted into steam. This 80 steam, while having a chilling influence upon the wall of the casting so as to prevent warping thereof, will maintain the gaseous fuel within the chamber 4 at a much higher temperature than would be possible 85 should water circulate freely in the chamber 9. Consequently the efficiency of the engine is greatly increased inasmuch as it is possible to keep the temperature of the fuel but slightly below the temperature at which 90 it will ignite in the explosion chamber. Obviously valve 11 can be regulated so as to vary the supply of water to the chamber 9 to meet different climatic conditions and to insure the maintenance of the heat of the wall 95 at approximately a predetermined temperature. A steam vent 14 may be provided in the top of the chamber 9 so as to obviate the danger of explosion due to steam pressure within the engine or radiator. 100

What is claimed is:—

1. In an explosive engine, a cylinder casting having a water jacket and a steam chamber, valved means for controlling the admission of water to the steam chamber from 105 the water jacket, and exhaust and fuel passages extending into the steam chamber.

2. In an explosive engine, a cylinder casting having a water jacket and a steam chamber, valved means for controlling the admission of water from the water jacket into 110 the steam chamber, and exhaust and fuel

passages extending into the steam chamber, said steam chamber having a vent.

3. In an explosive engine, a cylinder casting having a water jacket, exhaust and fuel 5 passages extending into the casting, a partition within the casting and providing a steam chamber extending between the passages, said partition having a port for maintaining communication between the water 10 jacket and the steam chamber, and means for controlling the flow of water into the steam chamber from the jacket.

4. In an explosive engine, a cylinder casting having a steam chamber, means for admitting water in minute quantities to the steam chamber from the water jacket, and 15

means for conducting gaseous fuel and exhaust gases through the steam chamber.

5. In an explosive engine, a cylinder casting having a jacket including a water chamber and a steam chamber, valved means for controlling the flow of water from the water chamber into the steam chamber, and means for conducting exhaust gases and gaseous fuel through the steam chamber.

In testimony that I claim the foregoing as my own, I have hereto affixed my signature in the presence of two witnesses.

LE ROY BROWN.
